UNITED STATES PATENT OFFICE.

CHARLES CHRISTENSEN, OF VANCOUVER, WASHINGTON.

AIR CLEANER.

Application filed August 23, 1920, Serial No. 405,536. Renewed March 9, 1926.

This invention has reference to air washers for use in connection with explosion engines where the atmosphere is liable to be charged, to a detrimental extent, with dust.

5 The object of the invention is to free the air entering the air intake of the carbureter used in connection with an internal combustion engine from dust or other impurities and to charge the cleansed air with watery 10 vapor in a warm condition, warmth and moisture contributing markedly to the efficiency of the engine.

In accordance with the invention there is provided a casing having an air intake and 15 an air outlet, the latter being arranged to be connected to the air intake of the carbureter. The air intake is located at a high point in the casing, and in the path of the stream of air entering the intake there is a chamber 20 containing a series of staggered perforated partitions designed to conduct water and air so that dust which may occur in the air stream is gathered up and directed to a body of water contained in the casing and 25 the water is finally returned to the inlet of the radiator of the automobile, the return connection being located high enough so that the portion of the casing below the level of 30 the water returned to the radiator constitutes a mud drum. Water is conducted from the water jacket of the engine into the casing above the perforated partitions so as to gravitate through alternate ends of the partitions in order. Provision is made for 35 the occasional draining of the casing to remove accumulations of dust in the form of mud.

The invention will be best understood from a consideration of the following detailed description taken in connection with 40 the accompanying drawings forming part of this specification, with the understanding, however, that the invention is not confined to any strict conformity with the showing in the drawings, but may be changed and modified so long as such changes and modifications mark no material departure from the salient features of the invention as expressed in the appended claims.

50 In the drawings:

Fig. 1 is a vertical diametric section through an air cleanser or washer embodying the invention.

55 Fig. 2 is a top plan view with some parts in cross section in a lower plane immediate-

ly below the water inlet and also in part cutting the latter.

Fig. 3 is a cross section in a lower plane than the sectioned portions of Fig. 2 and omitting the return duct to the radiator. 60

Figure 4 is an elevation of the motor and radiator with the invention applied thereto.

Referring to the drawings there is shown a casing or body member 1, conveniently made cylindrical although not necessarily 65 confined to such particular shape. It is connected to the engine and radiator as shown in Figure 4 and is placed high enough to allow the water to flow by gravity. The body member 1 has two heads 2 and 3 with 70 the head 2 uppermost, for the structure when installed is upright. The head 2 is solid or unbroken for about half its width and the remainder of the head is formed of gauze indicated at 4, although other foraminous or 75 perforated material may be employed. The head 3 is provided with a screw plug 5 held in place by a lock nut 6, but the arrangement may be different so long as provision is made for drawing out accumulations from 80 the lower part of the casing 1, constituting a mud drum 7.

At a relatively high point in the casing is a outlet pipe 8 arranged to be connected to air intake of the carbureter of 85 the explosion engine with which the air cleaner is to be associated.

At a distant point in the chamber 1 from the outlet pipe 8 and sufficiently low therein to be somewhat above the mud drum, is 90 another outlet pipe 9 designed to be connected to the intake portion of the radiator, of the explosion engine.

In the upper portion of the casing 1 there is a chamber 10, formed in most part by the 95 walls of the casing 1, and having a partition 11 extending across the casing. The partition 11 and chamber 10 are upright like the casing 1 while the bottom of the chamber is formed by a partition 12 above which 100 are arranged other partitions 13. Within the chamber above the topmost partition 13 is a pipe 14 extending diametrically across the chamber from side to side parallel with the partition 11, said pipe being connected with the water jacket of the engine. Each partition 12 and 13 is arranged substantially 105 horizontally and is provided near one edge with a passage 15 therethrough and has perforations 16 or the like adjacent to the pas- 110

sage 15. Between the perforations 16 and the other edge of the partition the latter is imperforate.

The pipe 14 has perforations 17 there-through for a portion of its circumference and directed toward the imperforate part of the uppermost partition 13.

With the air washer properly installed between the radiator and the carbureter as shown in Figure 4 so that a stream of air may be directed through the air washer, a stream or spray of hot water is directed through the perforations 17 on to the uppermost partition 13, to flow over the perforations 16 in the partition, through which the water drops to the imperforate part of the next underlying partition, to flow through the perforated part thereof, and drop on to the imperforate part of the next partition, and so on, the water finally passing through the lowermost partition into the mud drum where the water level may approximate the level indicated by the dotted line 18.

The suction of the engine draws air through the head 2 into the chamber 10 where the air is directed about the pipe 14 and through streams of water issuing from the said pipe 14 by way of the perforations 17. The water readily takes up the particles of dust and as the water falls upon the uppermost partition 13 it carries the dust particles with it, so that the air, on reaching the passage 15 in the uppermost partition 13, is much cleaner than when it entered the casing 1. The air stream continues its course through the casing 1, through a path rendered tortuous by the staggered relation of the groups of perforations 16 and the passages 15. After passing through the lowermost partition 12 the water falls to the lower portion of the casing 1 constituting the mud drum, for flow back to the inlet of the radiator through the outlet pipe 9, while the cleansed air passes through the outlet pipe 8 and from thence to the air intake of the engine carbureter.

The result is that only thoroughly cleansed air reaches the carbureter and this air is warmed air since it has been caused to traverse streams of water previously heated in the water jacket of the engine. The invention has the advantage of contributing to the vaporization of the fuel because of the pre-heating of the air mixed with the fuel in the carbureter, while the effect on the radiator is to reduce the temperature of the water entering the radiator, the passage of the water through the partitions serving to eliminate the heat therefrom. These advantages are in addition to the principal advantage of the invention, which is to render it feasible to use the engine in atmospheres heavily charged with dust particles. Such atmospheres are particularly liable to be met with in farming operations where

dust is often plentiful and dense and unless the air reaching the carbureter is clean the cylinders, pistons and valves of the engine will be quickly and seriously harmed, requiring frequent repairs and consequent heavy expense.

By means of the invention herein disclosed, I am able to supply clean, moist, warm air to the carbureter of the engine, and in return deliver to the radiator cool water deprived of any dust, the circulation of the water being continuous and effected without a circulating pump.

What is claimed is:

1. An air washer and charge humidifier adaptable for connection between the radiator, water jacket and carbureter of an internal combustion engine comprising a casing having an air inlet for taking air from the outside atmosphere, an air outlet, a perforated water inlet pipe located at a high point in said casing below the air inlet for delivering a spray of water in the path of the incoming air, an outlet pipe low in the casing but above the bottom thereof for delivering water therefrom, and a chamber in the casing having perforated partitions with the perforations in the several partitions in staggered relation, said chamber being located below the water inlet and above the water outlet pipe and spaced from the air outlet pipe, whereby the air is caused to pass through streams of water before it reaches the air outlet pipe on its way to the engine carbureter.

2. An air washer and charge humidifier adaptable for connection between the radiator, water jacket and carbureter of an internal combustion engine comprising a casing, a chamber within the casing having partitions each with a passage for air there-through, and a plurality of perforations located at one side of the air passage to permit water and air to escape therethrough, the passages in the partitions being in staggered relation, a water inlet within the casing at a high point thereof provided with perforations adapted to produce a water spray, with the spray directed toward one of the partitions to flow to the next partition in order, an outlet for the water below the chamber leading from the casing, an air outlet for the casing spaced from the chamber, and an air inlet for the casing at the top above the water inlet so that the air is sprayed with warm water as it enters the casing, the air passing from the inlet through the partitions to the air outlet and caused to follow a tortuous path in traversing relation to the stream of water flowing from one partition to another.

3. An air washer and charge humidifier adaptable for connection between the radiator, water jacket and carbureter of an internal combustion engine comprising a cas-

ing having an air inlet located in the top thereof, a chamber therein confined to the upper portion of the casing and embracing the air inlet, a series of partitions in the casing, each partition having an opening in one end, imperforate at the other end, and perforated intermediately, each partition having its imperforate end beneath the imperforate end of the next higher partition, whereby to direct air and water entering the chamber back and forth between the partitions, means for delivering a spray of water on the uppermost partition and in the path of the air entering the air inlet, an out-

let for water at the lower end of the casing 15 above the bottom but below the chamber, and an outlet for air at the upper portion of the casing spaced from the wall of the chamber, the openings at the end of each partition providing a passage for substantially 20 the greater volume of the air, while the perforated portions of the partitions provide a passage for substantially the greater volume of the water.

In testimony, that I claim the foregoing 25 as my own, I have hereto affixed my signature.

CHARLES CHRISTENSEN.
